INERTIA STARTER

Samuel Gilbert, Cedar Grove, N. J., assignor to
 Bendix Aviation Corporation, Teterboro, N. J.,
 a corporation of Delaware

Application January 24, 1949, Serial No. 72,395

6 Claims. (Cl. 123—179)

1

The present invention relates to starters and more particularly to the type of starter wherein a flywheel is energized to a high speed of rotation and then engaged to the engine to be started to crank it.

In starters of this type, it has long been recognized that it is highly desirable that the driving output member of the starter and the driven member of the engine, usually a pair of mating jaws, be engaged prior to the engagement of the rotating flywheel to the starter output member. Various means and methods for engaging the starter and engine jaws prior to the engagement of the flywheel have been proposed but most of the proposed means and methods have had various drawbacks, the most serious of which being rotation and transmittal of torque by the starter jaw element at the instant of engagement with the engine jaw element and the complicated expensive and bulky construction of such prior art starters in general.

An object of the present invention is to provide an improved engine starter of the inertia type which is of simple construction and effective operation.

Another object of the present invention is to provide novel means for causing the engagement of the starter jaw with the engine jaw prior to the operative engagement of the inertia member to the starter jaw in an inertia type starter.

Still another object of the present invention is to provide novel means in an inertia type starter whereby the starter jaw element is advanced into engagement with the engine jaw at element zero speed and zero torque.

The above and other objects and features of the invention will appear more fully hereinafter from a consideration of the following description taken in connection with the accompanying drawings wherein one embodiment of the invention is illustrated by way of example.

In the drawings, Figure 1 shows a view partly in elevation and partly in section of a starter embodying the novel means of the present invention.

Figure 2 shows a cross-sectional view of Figure 1 along the line 2—2.

Referring now to the drawings wherein like reference characters indicate like parts in the two figures, there is shown in Figure 1, an inertia starter enclosed in housing 10 comprising a jaw advancing mechanism housing portion 12, gear housing portion 14, and motor housing portion 16 held together in any convenient manner such as by studs and nuts as shown. The construction

2

of the jaw advancing mechanism may be of the type described in the copending U. S. application Serial No. 673,069, filed May 29, 1946 entitled Engine Starter and the Like and assigned to the same assignee as the present application, or such jaw advancing mechanisms may be of a type well known in the art. Illustration and description thereof has been omitted in order to render a more clear presentation of the novel features of the present invention. Such jaw advancing mechanisms comprise, in general, a rotating barrel 18 driven as from an internal gear 16 and adapted to drive an axially stationary long-lead screw 15 through a preset torque limiting friction disc pack clutch 17. The long-lead screw advances the jaw member 19 until a usual shoulder 21 on the jaw member abuts a usual corresponding shoulder 23 on the long-lead screw thus causing rotation of the jaw member by further rotation of the barrel. Internal gear 18 and driving pinion 20 are rotatively mounted on stub shafts 22 and 24 respectively, which are journaled in ball bearings supported in wall portion or partition 26 of clutch housing portion 14. The other end of stub shaft 24 is journaled in bearing 28 supported in wall portion 30 secured to a shoulder 32 of clutch housing 14 as by screws 34, which wall portion also supports ball bearings 36 in which a hollow motor shaft 38 is journaled. The starter motor is indicated at 40. Motor shaft 38 supports and is keyed or splined to rotatable inertia member or flywheel 42. The flywheel may, of course, also be rotated by a hand crank unit or other means well known in the art. Motor shaft 38 is terminated in driving means such as a pinion 44. The construction so far described is conventional and well known in the art and forms no part of the present invention. In the conventional inertia type starter pinion 44 is arranged to drive internal gear 18 either directly or through a reduction gearing and the whole gear train is put into motion when the flywheel is brought up to speed. A spring loaded meshing rod is provided for keeping the starter jaw away from the engine jaw during the acceleration of the flywheel and when the flywheel has attained a predetermined operating speed, the meshing rod is actuated either manually or by means of a solenoid to engage the starter jaw with the engine jaw. In the novel starter of the present invention a jaw meshing rod is not used. Friction against the jaw element together with the action of the rotating axially stationary nut on the screw shaft connected to the jaw element, as explained in my aforementioned copending U. S.

application, will cause the starter jaw to advance and engage the engine jaw as soon as the flywheel is put in motion and complete engagement is usually accomplished within the first revolution of the flywheel. A suggestion has been advanced to provide means whereby the tension in the torque limiting friction disc pack of the jaw advancing mechanism is released whereby just sufficient friction remains in the disc pack to advance the jaw element but to slip after the starter jaw is engaged to the engine jaw and then to reapply the tension to the disc pack when the flywheel has attained operating speed. However, it is highly important that the tension of the torque limiting disc pack be accurately preset so as to provide ample torque for cranking the engine yet be able to protect the starter mechanism should the engine abnormally resist cranking or if it should backfire, throughout the life of the starter. The above-mentioned method of periodically releasing the tension of the disc pack would make such accurate presetting of the torque limiting value practically impossible.

In the present invention, means are provided for operatively connecting driving means 44 with internal gear 18 of the jaw advancing mechanism whereby sufficient torque is transmitted thereto from the driving means to operate the jaw advancing mechanism but insufficient to transmit appreciable torque thereto after engagement of the starter jaw with the engine jaw including means for increasing the torque transmitting capacity of said connecting means to a value substantially higher than the torque limiting value of the disc pack of the jaw advancing mechanism.

In the particular embodiment shown in the drawings the connecting means between pinion 44 and internal gear 18 of the jaw advancing mechanism is shown as a disc type friction clutch generally indicated at 46 having friction discs 48 and 50 alternately internally splined to annular hub portion 51 of ring gear 52 and externally to hub 54 keyed to the stub shaft 24 as by key 56, respectively, but another type of clutch such as an internal expanding clutch or a cone type clutch in and of itself well known in the art may, of course, be found more suitable for certain applications.

In the disc type clutch shown for the sake of illustrating the principle of the present invention, the interleaved discs are backed by a ring member 58 held against flange 60 forming part of and extending inwardly from ring gear 52. Annular ring member 62 is internally splined to annular hub portion 51 so as to rotate therewith but axially slidably therein and is kept in position as by a snap ring 64 in an annular groove. Annular ring member 66 has an axially extending hub portion 68 adapted to receive the inner race of ball bearing 70 whose outer race is securely mounted in ring member 62. Adapted to press axially against ring member 66 so as to urge discs 48 and 50 against each other is a lever 72 having a forked end 74 straddling shaft 24 and being pivotally mounted between end portions 76 of slotted protrusion 78 of wall portion 26 by means of a pin 79. The end of lever 72 opposite the forked end 74 has a flat surface 80 resting against an operating rod 82 extending through the hollow shaft 38 which rod when actuated will move surface 80 to the left as seen in the drawing thereby pressing discs 48 and 50 against the backing ring 58 through ring members 66 and 62 and bearing 70 thus in effect locking ring

5 gear 52 to hub 54. Operating rod 82 may be operated by electromagnetic means such as a solenoid actuated by manually operated switch or by a centrifugal switch connected with the flywheel, manually, or by the use of a governor depending on the particular application to which the invention is placed.

In operation, the flywheel 42 is rotated, in this particular embodiment, by motor means 40. Operating rod 82 in its retracted position as shown exerts little or no force against lever 72. Although discs 48 and 50 are not pressed together, the inherent friction or drag between the interleaved discs will transmit sufficient torque from pinion 44 to hub 54 to rotate shaft 24 thus actuating the jaw advancing mechanism until jaw 19 meshes with a mating engine jaw (not shown). As soon as meshing of the jaws occurs, the reaction will increase the load and cause the friction discs 48 and 50 to slip relative to each other. If it is found that friction discs fail to transmit sufficient torque to actuate the jaw advancing mechanism, it may be pre-loaded as by spring means forcing operating rod 82 to the left as viewed in the drawing. It is to be noted that in this arrangement, the starter jaw is advanced at substantially zero torque and zero rotational speed. When flywheel 42 attains operating speed, operating rod 82 is actuated towards the left. Forcing surface 80 of lever 72 to the left will press forked end 74 against ring member 66 and thus force friction discs 48 and 50 against each other through bearing 70 and ring member 62 thus effectively locking ring gear 52 to hub 54 and permit flywheel pinion to crank the engine through pinion 20 and internal gear 18 of the jaw advancing mechanism. It should be noted that even if rod 82 were actuated by snap action, the clutch mechanism 46 will take most of the shock loading which otherwise would have to be absorbed by the starter gearing.

If the engine offers abnormal resistance to turning, or, if it backfires, the preset torque limiting disc pack 46 of the jaw advancing mechanism will slip and thus protect the operating parts of the starter against excessive and destructive loading. The friction clutch 46 should be designed so that it will have a substantially higher equivalent slip value in locked position than the torque limiting disc pack in order to insure proper operating and protection characteristics of the starter.

Although only one embodiment of the invention has been illustrated and described, various changes in the form and relative arrangements of the parts may be made to suit requirements.

What is claimed is:

1. In an engine starter the combination of a rotatable extendable driving member adapted to engage and drive a driven member of an engine to be cranked, a driving member advancing mechanism including preset torque limiting means, a flywheel, means for rotating said flywheel and storing energy therein, means including gearing for connecting said flywheel to said driving member, advancing means comprising a disc clutch normally released but having sufficient drag to operate said advancing mechanism to advance said driving member into engagement with said driven member but insufficient to crank said engine when the flywheel is rotated, means including a pivoted member pressing said discs together and actuated by an operating rod for increasing the slip value of said disc clutch 75 to a value substantially higher than said torque

limiting means thereby establishing driving connection between said flywheel and said driven member when said flywheel has attained a predetermined rotative speed.

2. In an inertia starter comprising, in combination, a flywheel, means for actuating said flywheel, driving means driven by said flywheel, a clutch, an engine engaging jaw, a jaw advancing mechanism including torque limiting means, said clutch being operatively connected with said flywheel and said jaw advancing mechanism and having a drag in released position sufficient to cause said jaw advancing mechanism to bring said jaw into engagement with a jaw of the engine to be cranked upon initial rotation of said flywheel, and means including a lever member for increasing the drag on said clutch member upon said flywheel attaining a predetermined speed to operatively connect said flywheel to said driving means to crank said engine.

3. In an inertia starter having a rotatable inertia member and driving means therefor, an extendable and rotatable jaw, and a jaw advancing mechanism including a preset torque limiting means; the combination comprising a clutch interposed between said rotatable inertia member and said jaw advancing mechanism having sufficient drag in released position to operate said jaw advancing mechanism to advance said jaw into engagement with a corresponding jaw of an engine to be started upon initial rotation of said inertia member and adapted to slip when said jaws engage, and means to adjust said clutch to a higher slip value to effect rotation of said engine jaw by said inertia member.

4. In an inertia starter having a rotatable inertia member and means for rotating said inertia member, an extendable rotatable jaw member adapted to engage a jaw of an engine to be cranked, means for advancing said jaw member including torque limiting means, means independent of said torque limiting means for transmitting sufficient torque from said inertia member to said jaw advancing mechanism to advance said jaw member into engagement with the engine jaw but insufficient to crank said engine upon initial rotation of said inertia member, and means for increasing the torque transmitting capacity of said transmitting means to a

value sufficient to crank said engine, said last value being substantially higher than said torque limiting means of said jaw advancing means.

5. A starter having a rotatable inertia member and means for rotating said member and storing energy therein, a rotatable extendable jaw element adapted to drivingly engage a mating jaw element of an engine to be started, the driving connection between said inertia member and said starter jaw comprising a jaw advancing mechanism, a preset torque limiting means, and a friction clutch, said friction clutch having sufficient drag in released position to operate said jaw advancing mechanism to bring said jaws into engagement but insufficient to crank the engine upon initial rotation of said inertia member, and means for operating said friction clutch to effect a higher slip value than said torque limiting means, thereby completing the driving engagement to the engine to be started when said member has attained operating speed.

6. In an engine starter having a driving member, means for extending and driving said member, a flywheel, means for rotating said flywheel and storing energy therein, the combination of means for operatively connecting said flywheel to said extending and driving means comprising a gear train, preset torque limiting means, and friction clutch means, said friction clutch means being normally in released position having sufficient frictional drag to extend but insufficient to drive said member upon initial rotation of said flywheel, and means for actuating said clutch upon said flywheel reaching a predetermined speed to have sufficient frictional drag to drive said member and having a torque transmitting capacity substantially higher than the torque transmitting capacity of said torque limiting means.

40 SAMUEL GILBERT.
